UNITED STATES PATENT OFFICE.

HAROLD JARVIS, OF BUFFALO, NEW YORK.

DESIGN FOR A BICYCLE-FRAME.

SPECIFICATION forming part of Design No. 34,673, dated June 18, 1901.

Application filed May 18, 1901. Serial No. 60,943. Term of patent 14 years.

To all whom it may concern:

Be it known that I, HAROLD JARVIS, a citizen of the United States, residing at Buffalo, in the county of Erie and State of New York, have invented and produced a new and original Design for a Bicycle-Frame, of which the following is a specification, reference being had to the accompanying drawings, forming a part thereof.

This design relates to the shape or configuration of bicycle-frames.

The accompanying drawing is a perspective view of a bicycle-frame embodying my design.

As shown in the drawing, the leading or material feature of my design consists of a triangular rear frame A, a seat or saddle post B, arranged on the front side of the front member a of said frame, a steering-head C, an upper reach member D, extending rearwardly and downwardly from the upper portion of the steering-head to the middle portion of the saddle-post B, a hanger-sleeve E, a lower front reach member F, extending downwardly and rearwardly from the lower portion of the steering-head to the hanger-sleeve E, and a lower rear reach member F', extending from the hanger-sleeve to the lower front corner of the triangular rear frame A.

The rear members a' a² of the triangular frame are forked, as shown. The saddle-post 30 B is substantially parallel with the member a and terminates below the upper end thereof. g represents braces which connect the saddle-post with the adjacent member a.

h is an inclined brace extending from the 35 central portion of the upper reach member D to the hanger-sleeve E, and i is a substantially vertical brace arranged between the inclined brace h and the saddle-post B and extending from the upper reach member to 40 the lower rear reach member F'.

j is a substantially upright handle-bar sleeve mounted on the upper reach member between the steering-head and the inclined brace h. 45

What I claim is—

The design for a bicycle-frame substantially as herein shown and described.

Witness my hand this 15th day of May, 1901.

HAROLD JARVIS.
